UNITED STATES PATENT OFFICE.

THOMAS BRANSON, OF PHILADELPHIA, PENNSYLVANIA, ASSIGNOR TO SIBSON & STERN, INC., OF GERMANTOWN, PHILADELPHIA, PENNSYLVANIA, A CORPORATION OF PENNSYLVANIA.

REINFORCING FABRIC STRIP FOR TIRES.

1,300,696.

Specification of Letters Patent. Patented Apr. 15, 1919.

Application filed March 11, 1918. Serial No. 231,714.

To all whom it may concern:

Be it known that I, THOMAS BRANSON, a citizen of the United States, residing in Philadelphia, in the county of Philadelphia and State of Pennsylvania, have invented 5 certain new and useful Improvements in Reinforcing Fabric Strips for Tires, whereof the following is a specification, reference being had to the accompanying drawings.

10 The invention relates more particularly to a fabric strip for tires which includes a series of substantially straight parallel cords extending lengthwise of the strip.

An object of the invention is to provide 15 a strip wherein the parallel cords extending lengthwise thereof and forming the body portion of the strip are connected by threads which are so arranged that the strip may be cut lengthwise without disintegrating said 20 cut portions.

A further object of the invention is to provide a reinforcing fabric strip of the 25 above character wherein the connecting threads include rows of enchain loops extending lengthwise of the strip, which enchain loops are sufficiently elastic to permit the cords when under tension to lie straight.

A still further object of the invention is 30 to provide a reinforcing fabric of the above character wherein the connecting threads include separated rows of enchain loops and connecting binding threads which join the rows of loops.

35 These and other objects will in part be obvious and will in part be hereinafter more fully disclosed.

In the drawings, Figure I, is an enlarged 40 plan view of a fabric having my improvements embodied therein.

Fig. II, is a similar view but showing a slightly modified form of arrangement of the connecting threads which sustain the 45 cords.

The invention is directed particularly to a reinforced fabric for tires, which includes a series of cords extending lengthwise of the 50 fabric strip. Prior to my invention, fabric strips of this character have been provided wherein the cords have been sustained by being interwoven with warp threads extending back and forth transversely of the 55 cords. In fabric strips of this character, the

cords are not only liable to pile one on top of the other, but the strips must be made in 55 the exact width in which they are to be used. The present invention is directed to the improved way of joining the cords wherein the cords are held from piling one on top of the other, and whereby the fabric 60 strip may be cut longitudinally without disintegrating the cut portions. I have accomplished this connecting of the cords in the present embodiment of the invention by using a series of rows of separately en- 65 chain loops extending longitudinally of the strip and connecting these enchain loops by binding threads, said enchain loops and binding threads being disposed between and about the cords 70 so as to join the same to form the fabric strips.

Referring more in detail to the drawings, I have shown my improved reinforcing fabric strip as consisting of a series of cords 1, 75 which extend substantially straight and parallel with each other and lengthwise of the strip, which is to be embodied in the tire. In the form of the invention shown in Fig. I, I have provided a series of rows of enchain loops 2. These rows of loops are each separately enchain and extend lengthwise of the fabric strip. In other words, the enchain series 2, consists of a loop 3, which encircles the base of the 80 next loop 4, and this loop 4, encircles the base of the loop 5. The loop 3, is brought from underneath the cord 1, at one side thereof, and extends across the cord. The loop, 4, is brought from underneath the opposite side of the same cord and extends across the same, and the loop 5, is again brought from under the same side of the cord 1, as the loop 3. Thus it will be seen that these enchain loops will completely envelop one 85 of the cords. Two binding threads are used. These binding threads are indicated at 6, and 7, and pass through one or more of the enchain loops extending about one of the cords, and then across to the next row of enchain loops extending about another cord. Preferably between the binding threads 7, and 8, is a cord 1, so that alternate cords 90 are enveloped by the enchain loops, and these alternate cords extend between the 95 binding threads.

It will readily be seen that if this fabric strip formed as shown in Fig. I, is put under tension, the enchain loops being elastic will yield sufficient so as to allow the cords to lie straight. It will also be readily seen that these enchain loops and binding threads hold the cords so that they are spaced from each other and prevent said cords from piling one on top of the other. By cutting the binding threads between two of the cords, the strips may be cut longitudinally and the enchain loops form a selvage edge which prevents the cut portions from disintegrating. Of course, it is understood that the cord held only by the binding threads would drop out when the strip is cut. This fabric strip may be made in any desired width most convenient to manufacture, and then may be cut to any desired width for use, depending upon the size of the tire into which it is to be embodied.

In Fig. II, of the drawing, I have shown a slightly modified form of the invention. The enchain loops indicated at 8, are similar in construction to the enchain thread loops indicated at 2, in Fig. I, with the exception that these enchain thread loops do not envelop the cord. The binding threads indicated at 9, and 10, are arranged slightly different from that shown in Fig. I. I have also shown two cords in this modification of the invention between two adjacent rows of enchain thread loops 8. The binding thread 9, passes over the two cords, while the binding thread 10, passes underneath the same. Thus the cords are held through the combined action of the enchain loops and the binding threads.

It will be obvious that other modifications in the general arrangement of the enchain thread loops and binding threads and also the cords may be made without departing from the spirit of the invention. The essential feature consists in connecting the threads for sustaining the cords so that the cords may be placed under tension and lie straight without bending, and so that the fabric strip may be cut longitudinally without disintegrating the cut sections of the strip.

Having thus described my invention, I claim:

1. A reinforcing fabric strip for tires comprising a series of straight parallel cords extending lengthwise of the strip, a series of rows of enchain thread loops extending lengthwise of the strip and binding threads extending lengthwise of the strip and connecting said enchain thread loops, said enchain thread loops and binding threads being disposed so as to connect and hold said cords, whereby said strip may be cut in a lengthwise direction between alternate binding threads. 55

2. A reinforced fabric strip for tires, comprising a series of straight parallel cords, extending lengthwise of the strip; a series of separately enchain rows of thread loops extending lengthwise of the strip; and binding threads extending back and forth between the adjacent rows of enchain loops, 70 said enchain loops and binding threads being disposed so as to connect and hold said cords. 65

3. A reinforced fabric strip for tires, comprising a series of straight parallel cords extending lengthwise of the strip; a series of separately enchain rows of thread loops each disposed so as to envelop one of said cords, and connecting binding threads joining adjacent rows of enchain loops. 75

4. A reinforced fabric strip for tires, comprising a series of straight parallel cords extending lengthwise of the strip; a series of separately enchain rows of thread loops extending lengthwise of the strip, said enchain thread loops being disposed so as to envelop alternate cords and binding threads joining rows of enchain loops, said binding threads being disposed so as to embrace and hold the intermediate cords between the 90 rows of enchain thread loops. 85

In testimony whereof I have hereunto signed my name at Philadelphia, Pennsylvania, this eighth day of March, 1918.

THOMAS BRANSON.
